Primary Examiner — Ramzi S Almatrahi(74) *Attorney, Agent, or Firm* — Burbage Law, P.C.;
Jon-Michael Burbage; Elizabeth Ruzich**(57) CLAIM**

The ornamental design for a camera globe, as shown and described.

DESCRIPTION

FIG. 1 is a top perspective view of a camera globe;

FIG. 2 is a top view thereof;

FIG. 3 is a bottom view thereof;

FIG. 4 is a left side view thereof;

FIG. 5 is a back view thereof;

FIG. 6 is a right side view thereof; and,

FIG. 7 is a front view thereof.

The broken lines depict portions of the camera globe in which the design is embodied that form no part of the claimed design.
